COATING APPARATUS

Stephen D. Klyce, Lexington, Mass., assignor to
 The B. F. Goodrich Company, New York, N. Y.,
 a corporation of New York

Application August 2, 1940, Serial No. 349,958

2 Claims. (Cl. 91—18)

This invention relates to coating apparatus and is especially useful in applying an adhesive to strips of material.

In the manufacture of rubber footwear many strips or pieces of rubberized fabric or rubber composition must be assembled and the operations of assembling have been conveniently accomplished by passing the work along a line of operators who adhere the pieces successively and roll or press them into place.

The present invention provides means enabling the operator to apply adhesive to such parts uniformly and without employment of both hands.

The principal objects of the invention are to provide for storage of the adhesive without excess evaporation of the solvent, to provide uniform application of adhesive, to provide for removal of excess adhesive, and to provide efficiency of operation and facility of manipulation.

These and other objects will appear from the following description and the accompanying drawing.

In the drawing:

Fig. 1 is a side elevation of the device with parts thereof cut away.

Fig. 2 is a plan view of the device.

Fig. 3 is a fragmentary sectional view of the cement applicator, cement scraper, and upper rear edge of the container.

Of the drawing, the numeral 10 designates a container for a supply of liquid adhesive 11 such as rubber cement. The container is preferably provided with a flange 12 upon which the container may be supported from the margins of a work table 13 surrounding an opening 14 in the top of the table. A plate 15 having perforations 16 therethrough is secured at one end to a shaft 17 journaled for rotation about a horizontal axis in bearings 18, 19 formed on the container above the adhesive. The plate normally rests in the container within the adhesive so as to prevent drying of the adhesive thereon but may be raised to a position parallel to the surface of the adhesive and above its surface, as shown in Fig. 1. In this position, a foot 20 formed on the free end of the plate engages an inwardly directed flange 21 of the container preventing further movement in a clockwise direction as viewed in Fig. 1. When so lifted from the adhesive, excess adhesive will drain off the plate through the perforations and over the edges leaving a uniform coating of adhesive which may be removed therefrom by contact with an article 22 applied thereto.

For lifting the plate 15, one end of shaft 17 is formed with a lever arm 23. Additional lifting

means may be provided such as a lever 24 pivotally suspended as at 25 from the table 13 in a position to be engaged by the knee of an operator, and connected to lever 23 by a link 26.

5 For removing excess adhesive from the work and for returning it to the container, a bar 30 is supported horizontally from and above the plate 15 over an opening 31 formed in the plate. As the article 22 is dragged across the surface of the plate any excess adhesive is scraped from its surface by the bar and returns to the container.

The inwardly directed flange 21 at the top of the container extends thereabout and in its innermost edge is downwardly directed, as at 31 so as to return any adhesive dropped thereon directly to the body 11 of adhesive thereby preventing running of adhesive down the sides of the container where it might dry from evaporation.

By supporting the container in a recess of the table it is well out of the operator's way and cannot be upset.

In the operation of the apparatus, the plate 15 normally remains below the surface of the adhesive in the container where it is free from dust or dried deposits of cement. When a part is to be cemented, the operator shifts a knee laterally against arm 24 thereby raising plate 15 above the container with adhesive thereon. Excess adhesive drains off. The article is then dragged across the plate and over the scraper bar 30 to provide an even coating of adhesive on the article.

Variations may be made without departing from the scope of the invention as it is defined by the following claims.

I claim:

1. Coating apparatus comprising a container for adhesive, a plate normally submerged in adhesive within said container, means for raising said plate at will to a position above said container, and scraper means mounted on said plate to remove excess adhesive from an article.

2. Coating apparatus comprising a table having a recess therein, a container for adhesive adapted to be seated in said recess, a plate normally submerged in adhesive within said container, said plate being pivotally mounted for movement to a position above said container, stop means for limiting such movement, a scraper bar mounted on said plate for removing excess adhesive from an article and returning it to said container, and pedally operated means for swinging said plate from its submerged to its elevated exposed position.
